(74) Attorney, Agent, or Firm — Will Hunziker

(57) **CLAIM**

The ornamental design for a hexagonal container, as shown and described.

DESCRIPTION

1. Hexagonal container
- 1.1 : Perspective
- 1.2 : Top
- 1.3 : Bottom
- 1.4 : Front
- 1.5 : Back
- 1.6 : Left
- 1.7 : Right
- 1.8 : Perspective exploded
- 1.9 : Top exploded
- 1.10 : Bottom exploded
- 1.11 : Left exploded
- 1.12 : Right exploded
- 1.13 : Front exploded
- 1.14 : Back exploded
- 1.15 : Perspective exploded

1 Claim, 15 Drawing Sheets
